CLAIM

The ornamental design for a monitor display, as shown and described.

DESCRIPTION

FIG. 1 is a front elevation view of a monitor display showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof;

FIG. 9 is another perspective view of the monitor display of FIGS. 1-8 in a folded position;

FIG. 10 is a perspective view in the folded position thereof;

FIG. 11 is an enlarged view of the encircled portion '11' in FIG. 10;

FIG. 12 is an enlarged view of the encircled portion '12' in FIG. 3; and,

FIG. 13 is an enlarged view of the encircled portion '13' in FIG. 6.

The even-dash broken lines depict portions of the monitor display that form no part of the claimed design.

The dash-dot broken lines in FIGS. 3, 6, 10, 11, 12 and 13 indicate the limits of the enlarged views and form no part of the claimed design.

1 Claim, 13 Drawing Sheets
